CLAIM

The ornamental design for the tire, substantially as shown and described.

DESCRIPTION

FIG. 1 is a perspective view of a tire showing our new design, it being understood that the tread pattern repeats circumferentially throughout the outer circumference and shoulder of a tire, the opposite side perspective view being identical thereto.

FIG. 2 is a side of the tire.

FIG. 3 is a front elevation view of the tire.

FIG. 4 is a front elevation view of a portion of the tire indicated in FIG. 3; and,

FIG. 5 is a perspective view of a portion of the tire indicated in FIG. 1.

The broken lines depict environmental subject matter only and form no part of the claimed design; the broken lines immediately adjacent to the tire shoulder represent boundaries of the claim.

1 Claim, 4 Drawing Sheets
